UNITED STATES PATENT OFFICE.

THADDEUS LOWE, OF SAN MARINO, CALIFORNIA.

APPARATUS FOR HEATING ORCHARDS.

1,375,221.

Specification of Letters Patent. Patented Apr. 19, 1921.

Application filed March 8, 1919. Serial No. 281,503.

To all whom it may concern:

Be it known that I, THADDEUS LOWE, a citizen of the United States, residing at San Marino, in the county of Los Angeles and State of California, have invented a new and useful Apparatus for Heating Orchards, of which the following is a specification.

My invention relates to the apparatus of producing artificial heat in groves, orchards and kindred places where it is essential to prevent the temperature of the atmosphere from falling to such an extent as to injure or damage the fruit. In localities where citrus fruits are raised it occasionally happens that during some nights the temperature for short intervals will fall to such a low degree that the fruit is spoiled, and it is desirable to use some means whereby the temperature of the orchard may be moderated to prevent damage of the fruit.

One of the main objects of my invention is to produce an apparatus of simple form and construction in which any commercial fuel may be used, consisting of a central heat producing apparatus wherein great quantities of heat are produced, the fuel being substantially entirely consumed after which the heat is conducted through the orchard through a system of radiation pipes or conductors, there being used one or more mechanically operated exhausters to facilitate the distribution of heat through the radiator pipes or conductors.

A further object is to arrange such conductors in units that may be readily handled and which may be quickly placed together to form the system.

Other objects and advantages will appear hereinafter from the following specification.

Referring to the drawings, which are for illustrative purposes only,

Figure 1 is a diagrammatic plan view of an orchard or grove showing a heating system embodying a form of my invention.

Fig. 2 is a sectional elevation of the furnace or heat producer used in my system.

Fig. 3 is a side elevation of the furnace shown in Fig. 2.

11 designates a furnace having a heat non-conducting lining 12 and a smoke stack 13 provided with a suitable valve or damper 14. 15 designates a fuel chamber, 16 grate bars and 17 a door through which fuel may be placed in the furnace, 18 designating an opening in the front wall of the furnace through which a liquid fuel burner (not

shown) may be inserted if it is desired to use such fuel instead of solid fuel.

20 designates an elongated combustion chamber connecting through a damper or valve 21 with the main heat conductor 22, such conductor having an opening 23 in one side for connecting to a distributing conductor 24 as shown in Fig. 1. 25 designates a blower of any well known form connected by a pipe 26 with the fuel chamber 15 under the grate 16, a suitable valve 27 being provided in the pipe 26 by means of which air passing to the fuel chamber through the pipe 26 may be regulated. 28 designates an air by-pass pipe in open communication with the pipe 26, such pipe 28 entering the furnace in alignment with the combustion chamber 20 as clearly shown in Figs. 1 and 2, such pipe 28 being provided with a suitable valve 29 by means of which the air passing through such pipe may be regulated.

The furnace is also provided with a fuel door 30 in one side thereof opening into the fuel chamber, a door 31 opening into the furnace beneath the grate, a door 32 to the combustion chamber, the stack 13 being provided with a door 33 and the main conductor being provided with a door 34, all shown in Fig. 3 of the drawings.

The furnace or heat producing unit in the system illustrated in Fig. 1 is preferably placed in one corner of the orchard 35, such orchard being diagrammatically illustrated by rows of trees 36. The main conductor 22 is connected to conductors 40 and 41 which are arranged longitudinally with respect to the furnace and connected by means of transverse conductors 42 and 43 respectively with a conductor 44. The conductor 44 has an open end 45 to which is attached an exhaust fan 46 of any common form, the exhauster 46 being provided with a pulley 47 which is driven by any suitable power source (not shown). The pipe 24 connects with the pipe 44 and is provided with a branch pipe 48 which extends substantially parallel to the pipe 44, being connected by a transverse pipe 49 with such pipe 44.

50, 50 designate valves by means of which the heat passing through the conductors or pipes may be regulated. All of the conductors are preferably made of sheet metal of good heat conducting material to more readily allow for quick radiation of heat, and are also preferably cylindrical in form, having any well known common form of slip

2 joints. These conductor pipes are preferably laid on the surface of the ground under the trees so that the heat is caught by the trees and spread laterally thereby. It is 5 understood, however, that the conductors may be placed above the surface of the ground, or if desired, may be even placed below the surface of the same.

10 The apparatus is operated in the following manner:

When it is desired to put the heating apparatus into operation I first close the valve 21 and then open the valve 14 so that the stack 13 is open. I then supply kindling or 15 other solid fuel to the fuel chamber through the door 30 or through the door 17. I then open the door 31 under the grate bars for the admission of air to produce combustion and ignite the fuel in the fuel chamber 15, 20 after which the door 30 or door 17 which has been opened is closed. When the fuel is thoroughly ignited and the furnace partially warmed and it is desired to use solid fuel I admit through the door 17 a charge 25 of fuel and then close such door. I then admit a limited amount of air through the valve 27 from the blower 25, which it is understood has been previously put in operation, being driven by any suitable power 30 source. I then close the door 31 and gradually admit more air through valve 27 and through valve 29 which induces combustion both in the fuel chamber 15 and the gases evolved therefrom in the combustion chamber 35 20.

While the furnace is heating and combustion is being properly regulated by the admission of air in proper proportions through the valves 27 and 29 I open door 40 34 and put into operation the exhauster 46, it being understood that this may be controlled from the furnace by any suitable well known form of electrical contrivance for that purpose. This is for the purpose 45 of purging the radiator or conductor pipes of dead air or any gases that may have leaked through the valve 21 and for the further purpose of facilitating the distribution of heat through the radiator pipes by the 50 vacuum producing tendency. I then close door 34 and open the valve 21, closing valve 14, and the resulting heat produced from the combustion of fuel supplied and gases evolved therefrom is forced and sucked 55 through the radiating or conductor pipes by the operation of the blower 25 and the exhauster 46 operating simultaneously. This operation plus the natural expansion of the air admitted to the furnace due to the heat 60 of the same produced by combustion assures a more even transmission of heat throughout the conductor pipes. The heat can also be regulated throughout the system of radiator pipes by regulating the position of the 65 valves 50 as may be required.

When it is desired to use liquid fuel such as crude oil, residuum or distillate or similar substances, the operation would be substantially the same except that instead of admitting fuel through the doors as heretofore referred to I admit the liquid fuel under pressure as is commonly done through the opening 18, the combustion taking place in the furnace and passing directly to the conductor pipes through the valve 21.

The elongated combustion chamber 20 is particularly to be noted as by this construction all smoke is consumed and the heated products passing to the conductors is only the non-combustible gases evolved.

It is understood that while I have shown a single furnace or heat producing device, as the diagram illustrated in Fig. 1 is of a small orchard, several furnaces may be arranged in connection with a single system 85 of conducting pipes if so desired, thereby covering an orchard or grove of considerable extent.

When the weather is such that the temperature may fall to near the danger point, 90 the furnace may be partially heated so that if it is necessary to put the apparatus in operation the same may be accomplished in a very short time.

Another advantage to be noted is that the 95 conductor pipes are preferably made in such lengths that they may be very quickly taken apart and stored during the warm months, and with proper care the system will last over a considerable period of time. 100

I claim as my invention:—

1. An apparatus for heating orchards and the like comprising a furnace having an elongated combustion chamber, means for delivering air under pressure to said furnace below the fuel, means for delivering air under pressure to said elongated combustion chamber above the fuel, a system of heat conducting pipes connected to said combustion chamber, and an exhauster connected to the outer open end of said conducting pipes.

2. An apparatus for heating orchards and the like comprising a furnace having a horizontally disposed elongated combustion 115 chamber, means for delivering air under pressure to said elongated combustion chamber above the fuel, a stack connected to said combustion chamber, means for cutting off communication between said stack and the 120 combustion chamber, a series of heat conducting pipes connected to said combustion chamber, valve means for regulating passage of heat from the combustion chamber to said pipes, and blower means connected 125 to said furnace to induce combustion therein and cause a flow of heat through said pipes.

3. An apparatus for heating orchards and the like comprising a furnace having an 130

elongated combustion chamber, a stack connected to said combustion chamber, means for cutting off communication between said stack and the combustion chamber, means 5 for introducing air under pressure to said furnace both above and below the fuel therein, means for regulating the amount of air delivered to the furnace, a series of heat conducting pipes connected to said combustion chamber, and valve means between 10 said combustion chamber and said pipes.

4. An apparatus for heating orchards and the like comprising a furnace having a

horizontally disposed elongated combustion chamber, means for delivering air under 15 pressure to said furnace above and below the fuel therein, a system of heat conducting pipes connected to said combustion chamber, and an exhauster connected to the outer open end of said conducting pipes, said 20 furnace having a lining of heat non-conducting material.

In testimony whereof, I have hereunto set my hand at Los Angeles, California, this 28th day of February, 1919.

THADDEUS LOWE.
